BURR

Oren B. Maxim and Roger M. Peabody, Waterbury, Conn., assignors to Scovill Manufacturing Company, Waterbury, Conn., a corporation of Connecticut

Application February 12, 1949, Serial No. 75,996

6 Claims. (Cl. 85—37)

1

This invention relates to rivets and burrs of the open-type such as used in attaching portions of garments together and especially for reinforcing the jointed seams of garments of the type used in the heavy work industries or play clothing for children.

This invention is an improvement on the construction shown in P. E. Fenton's Patent No. 1,783,113, dated November 25, 1930.

The object of this invention is to provide a burr which is so constructed as to prevent the rivet tack from being set on a bias to the axis of the burr setting and thus assure that the rivet tack head and burr will always be positioned parallel to the face of the seam of the cloth joint secured together.

Another object of this invention is to provide a burr with an inwardly set base wall having the maximum of flat expanse so that the rivet tack point in the setting operation will contact the base wall perpendicularly in any position and pierce axially therethrough without danger of biasing the rivet tack shank.

With this and other objects in view, the invention consists in certain novel features of construction hereinafter more particularly explained.

In the drawing:

Fig. 1 is a bottom plan view of the rivet burr.

Fig. 2 is a vertical sectional view through the burr.

Fig. 3 is an elevation of a form of rivet tack that is used in connection with the burr.

Fig. 4 shows a cross sectional view of the burr and a side view of the tack pierced through several plies of fabric just prior to the piercing of the burr.

Fig. 5 is a cross sectional view showing the burr and tack as they appear set upon the several plies of fabric, and

Fig. 6 is a view similar to Fig. 4 but showing the inherent fault of the prior burrs which my invention overcomes.

With the heretofore known open-type of burrs, there has been considerable difficulty experienced in controlling the axial alignment of the rivet tack and the burr during the setting operations. The reason for this was that the construction of the old burrs was such that they would have a tendency to bias the tack shank during the setting operation with the result that the head of the tack as well as the burr itself would not lie flush or parallel to the surface of the garment joint, and frequently the relative position of the burr and tack head would be considerably off from a

common center relative to each other. Also, the fact that the pointed ends of the conventional tack shanks are never in line with the center axis of the tacks was another factor that was the cause of defective burr setting with the old type of burrs. The new burr here disclosed is designed purposely to eliminate such faults and still make use of the conventional type of tack for the burr riveting operation.

Referring now to the drawing in which like reference numerals denote like parts throughout the several views, the numeral 10 designates generally an open-type burr comprising a flat annular flange 11 and a cylindrical barrel 12 formed upwardly from the center of said flange. The end of the barrel opposite from the flange is provided with a closed flat base end 13 that is set inwardly from the outer end 14 of the barrel and joined to it by an inturned supporting wall 15 and in contiguous relationship with the inner surface of the barrel 12.

As pointed out in the objects of the invention, the purpose of this burr is to attach several plies of material together such as might occur at a juncture seam or at the corner of a pocket construction on an overall garment. This is accomplished with the use of the above described burr 10 in cooperation with a rivet tack 16 which may be made of a suitable soft material to permit an easy balling over or upsetting operation of the shank coincident with the burr setting operation.

The rivet tack 16 is of the usual form of tack having a head 17, and a tapered shank 18 which is sheared off on opposite sides as at 19 to provide a sharp pointed end 20. As pointed out above, all conventional forms of tacks are never made so that their pointed ends are in direct alignment with the center axis of the shank. Thus in spite of the fact that a conventional tack 30 might be axially aligned with the apex 31 of a conical base 32 of an old type of burr 33 such as shown in Fig. 6, it was impossible to have the pointed end 34 of the tack 30 always strike the apex 31 with the result that the tack shank would be frequently biased in the setting operation and produce a defective burr setting. Experience has also shown that at times, if perchance the pointed end of the tack should start to pierce the inclined wall of the base 32 adjacent the barrel wall 35 of burr, it would carry a considerable portion of the barrel wall 35 up into the hollow of the burr, which would result in a weak as well as a lopsided burr setting.

In order to overcome the above faults and

assure that the tack 16 will always pierce through the closed base end 13 of the burr 10 in a perpendicular manner, this is accomplished in the present construction by making the base end 13 flat and over as large an area as would be permissible under normal manufacturing practices. To produce sufficient strength in the supporting wall 15 for the flat base 13 of a character to prevent the base end 13 from tearing out during the burr setting operation, the upper surface of the base 13 is joined to the inner surface of the wall 15 by a relatively large fillet as at 15a.

To facilitate the piercing of the tack point 20 through the base end 13 and also have the base end 13 as flat as possible throughout the entire expanse, the wall of this base is also reduced in thickness so that it will be somewhat less than the normal material thickness of the burr. This is accomplished by suitable punches striking the opposite surfaces of the base end 13 in the manner of a planishing operation and with a sufficient blow to drift or extrude the material of said base end outwardly and form up a surrounding rib 21 of the excessive stock, it being understood that the upper punch will be formed to provide for the fillet 15a.

In the setting of the burr fastener upon a garment seam, such as represented by the several pieces of fabric 22, the burr 10 and tack 16 may be machine fed to the opposite sides of the fabric plies 22 with the barrel end 14 of the burr 10 initially disposed against one surface of the plies 22 as shown in Fig. 4. The tack 16 will first pierce through the plies 22 and then the pointed end 20 of the tack will impinge and pierce through the base end 13 and pass up into the barrel 12 of the burr 10, where, by the use of suitable tools, the tack shank 18 will be balled over and clinched within the confines of the barrel 12 and at the same time the barrel 12 will force its way into the fabric plies 22 so that only the burr flange 10 and tack head 16 will remain exposed on the outside of the fabric plies 22. The rib 21, as provided in the planishing operation stated above, after the setting operation retains itself in the form of a shoulder within the burr such as to prevent the balled end of the tack shank from easily pulling out from the set burr, this shoulder being clearly shown in Fig. 5 as at 23.

In addition to the feature that the burr is designed so as to preclude a biased setting of the rivet tack relative to the garment, it also has the same advantages set forth in the rivet and burr construction as claimed for the Fenton patent referred to above in preventing the threads or fibres of the material to which they are applied from being drawn up through the hole in the burr base coincident with the burr setting operation.

It is, of course, obvious that minor changes in details of construction may be made for the disclosed rivet and burr without departing from the scope of the present invention as set forth in the appended claims.

We claim:

1. In a rivet burr construction for attaching a plurality of ply members together, a burr comprising a flange and a barrel extending from said

flange, said barrel having a closed end in the form of a flat base set inwardly from that end of the barrel opposite from the flange, and a rivet tack having a pointed end, said burr adapted to have its edge portion adjacent its base end set against the ply members, and said tack shank being driven through said ply members and through said flat base in a perpendicular manner at any point that the pointed end of said tack may contact said base, the shank of said tack being balled over or upset within the confines of said barrel to firmly clinch the tack and burr together through the ply members.

2. A burr construction as defined by claim 1 wherein substantially the entire expanse of said flat base is reduced in thickness relative to the normal stock thickness of said burr to facilitate the piercing of the tack shank therethrough.

3. A burr construction as defined by claim 1 wherein the flat base is reduced in thickness relative to the normal stock thickness of said burr and forming an annular rib about the inner surface of said base that serves as a shoulder to prevent the upset tack shank from easily pulling out from said burr.

4. A burr construction as defined by claim 1 wherein the flat base is set inwardly relative to the end of said barrel by an inturned peripheral wall contiguous with the wall of said barrel.

5. A burr comprising a flange and a cylindrical barrel extending from said flange, said barrel having a closed flat base end set inwardly from that end of said barrel opposite from the flange by a surrounding support wall, the material thickness of said base being less than the normal thickness of said burr, and a reinforcing rib surrounding said flat base opposite from its supporting wall.

6. A burr comprising a flange and a cylindrical barrel extending from said flange, said barrel having a flat closed end opposite from the flange, substantially the full expanse of said closed end being set inwardly from the end of said barrel by a supporting wall lying inside and contiguous with the inner surface of said barrel and providing a projecting annular rim of double wall thickness, the material thickness of said base being less than the normal material thickness of said burr and of a character to permit a tack point to readily penetrate therethrough.
